UNITED STATES PATENT OFFICE

172,478

DOLL OR THE LIKE

Elizabeth Raines, Beverly Hills, Calif.

Application July 1, 1953, Serial No. 25,756

Term of patent 14 years

(Cl. D34—2)

To all whom it may concern:

Be it known that I, Elizabeth Raines, a citizen of the United States, residing at Beverly Hills, in the county of Los Angeles in the State of California, have invented a new, original, and ornamental Design for a Doll or the like, of which the following is a specification, reference being had to the accompanying drawings, forming a part thereof.

I claim:

The ornamental design for a doll or the like, as shown.
